UNITED STATES PATENT OFFICE.

HAROLD A. BIERCK, OF PHILADELPHIA, PENNSYLVANIA, ASSIGNOR, BY MESNE ASSIGNMENTS, TO KINETIC ENGINEERING COMPANY, A CORPORATION OF PENNSYLVANIA.

PNEUMATIC CONTROLLER FOR MECHANICAL PIANO-PLAYERS.

1,241,812.

Specification of Letters Patent.

Patented Oct. 2, 1917.

Application filed August 21, 1911. Serial No. 845,809.

To all whom it may concern:

Be it known that I, HAROLD A. BIERCK, a citizen of the United States, residing in the city and county of Philadelphia, State of Pennsylvania, have invented a new and useful Pneumatic Controller for Mechanical Piano-Players, of which the following is a specification.

My invention consists of improved means 10 in a player piano for controlling power-actuated exhausting-means to be employed in connection with foot-actuated exhausting means.

It further consists of other novel features 15 of construction, all as will be hereinafter fully set forth.

The annexed drawings and the following description set forth in detail one mechanical form embodying the invention, such detail construction being but one of various forms in which the principle of the invention may be used.

Figure 1 is a front elevation of a self-playing instrument embodying my invention.

Fig. 2 represents a section on line $\alpha-\alpha$ of Fig. 1.

Fig. 3 represents a vertical section of a portion of the device embodying one form of my invention.

Fig. 4 represents a section on line $y-y$ of Fig. 3.

Fig. 5 represents a sectional detail of a slightly different form from that shown in Fig. 3.

Fig. 6 represents a section on the line $a-a$ of Fig. 5.

Fig. 7 represents an elevation of a portion of the pumping element in present use showing the point of attachment of my invention.

Fig. 8 represents a section on the line $z-z$ of Fig. 7, certain elements of Fig. 1 being omitted.

Similar numerals of reference indicate corresponding parts in all of the figures.

Referring to the drawings,

1 designates the case of an instrument embodying the features of a well-known type of player piano, in which the keyboard 2, pumping element foot treads 3 and air reservoirs or receivers 4 are familiar to those skilled in the art, as is also the exhaust chamber 5, connected as usual with the

player mechanism, and having outlet-openings 7 controlled by outwardly-opening valves 6, the foot treads 3 controlling the exhaust in said chamber, in the usual manner. 8 is a conduit, secured to one wall of the exhaust chamber 5 by suitable means, as screw 9, and having a plurality of ports 10 registering with ports 11 in the adjacent wall of the chamber 5, as seen clearly in Fig. 8.

12 is a partition in the conduit 8, as seen in Fig. 3, dividing the interior of said conduit into two chambers, an inlet chamber 13 and an outlet chamber 14. The former has communication by way of a port 15 with a chest or chamber 16, in the present instance the passage of air through said port 15 being controlled by a slide valve 17 slideable within the chamber 16, and in the form seen in Fig. 1, beneath the port 15 leading to the chamber 13 and the port 18 leading to the chamber 14. This valve has therein a port 19, which, when the valve is moved to its extreme left position, will register with the port 15, and when in this position the port 18 will be completely uncovered. When the valve 17 is moved to its extreme position to the right, as seen in Fig. 3, the port 15 will be entirely closed, but the port 19 in the valve will partially register with the port 18, so that the chambers 14 and 16 will at all times be in communication with each other.

20 designates a suction conduit connecting the outlet chamber 14 with a blower chamber 21, see Figs. 1 and 2, said conduit 20 having communication with the conduit 8 through the ports 18 and 19, the chamber 16 and port 15.

22 designates the air inlet to the blower chamber 21, and I have, in the present instance, shown in connection therewith a perforated plate or screen 23, the function of which is to muffle the sound by breaking up the column of air drawn into the blower. The chamber 21 is adapted to receive the blower or fan 24 for producing the suction, and there may be, as will be evident, any number of such fans employed in order to give the desired result in the pneumatic structure. As here shown, I have employed a single fan 24 suitably mounted with a key 25 on the shaft 26 for rotation therewith, the said shaft being driven by means of a motor

27, preferably operated by electricity. In connection with this motor, it will be noted that the terminal wires 28 lead to a point in close proximity to the operating mechanism of the instrument and are connected to a switch 29, by which the operation of the motor is controlled.

30 designates an outlet chamber located adjacent the blower chamber 21, and having 10 communication therewith by way of the port 31 while discharge to the atmosphere takes place through the outlet port 32. Attention is directed to a screen 33 which I preferably locate across the exhaust port 32 and which 15 serves a similar purpose to the screen 23, already described. The use of the screen structure over the inlet and outlet ports of the blower chamber is very important, since, as is well known, the noise of a blower is considerable, and I have found in practice 20 that this simple device substantially eliminates the same and makes the use of a cumbersome muffler mechanism unnecessary.

In connection with the blower apparatus, 25 just described, attention is directed to the fact that the same is preferably located beneath the floor 34 of the room in which the instrument is used, and connection is readily made by boring or drilling suitable holes in 30 the floor for the passage of the conduit 20 and the connections 28.

Referring now to the means for shifting and regulating the position of the valve 17, it will be noted that a valve rod 35 is connected at one end with the valve 17, and at 35 the other end to a lever 36 suitably pivoted at 37 and which terminates in an operating handle 38, located at a convenient point adjacent the key board. In the present instance, I show the handle 38 in close proximity to the usual handles 39 which control 40 respectively, the feeding of the perforated sheet roll and the loud and soft effects as produced by actuation of the pedals of an 45 ordinary instrument.

In Figs. 5 and 6 I have shown a slightly different form and arrangement of parts from that shown in Fig. 3, in that the conduit 20^a opens into the chamber 16^a through 50 a port 40, which, as seen in Fig. 6, is of substantially triangular shape, with its narrowest part toward the port 19^a in the valve 17^a, so that as the said valve is moved to the left 55 the valve-port will gradually uncover a greater port-area. This valve 17^a controls communication between the conduits 20 and 8, through port 15^a, as will be readily understood from Fig. 5.

A piano-player provided with the 60 closed invention may be played by foot-

power, by foot-power with the motor-actuated exhaust as auxiliary, by motor-actuated exhaust, or by motor-actuated exhaust with the foot power driven exhaust as an auxiliary, and the exhaust is at all times exerted in the one exhaust-chamber, whereby transitions from one form of exhaust to another, with accompanying volume and tension, will be accomplished smoothly and without shocks to the pneumatics and, consequently, to the keys of the instrument, whereby smooth performance, like that of the skilled human hands can be produced. As the power-driven exhaust is cut off by the valve when the foot-actuated exhaust is employed alone, there can be no leakage on 75 that side of the exhaust-chamber, and there can be no leakage through the chamber, reservoirs and pumps or bellows, when the power-actuated exhaust is employed, as increase of exhaust or part vacuum will assist in seating the outlet valves.

Other modes of applying the principle of my invention may be employed for the mode herein explained. Change may therefore be 85 made as regards the mechanism thus disclosed, provided the principles of construction set forth respectively in the following claims are employed.

Having thus described my invention, what 90 I claim as new and desire to secure by Letters Patent, is:—

1. In a device of the character stated, a blower chamber, an outlet chamber, a suction conduit connecting said chambers, an 95 exhaust chamber, a conduit communicating with said exhaust chamber, a slide valve having a port controlling the communication between the suction conduit and the conduit communicating with the exhaust chamber, the said outlet chamber having a port adapted to overlap the port in the slide valve when the latter is in one of its extreme 100 positions.

2. In a device of the character stated, a 105 blower chamber, an exhaust chamber, a conduit communicating with the exhaust chamber, a partition in said conduit dividing the same into inlet and outlet chambers, a chamber having ports whereby it is in communication with both the inlet and outlet chambers, and a slide valve having a port for register with said ports and arranged to overlap one of said ports when the valve is 110 in one of its extreme positions.

HAROLD A. BIERCK.
